US00D849382S

(12) **United States Design Patent** (10) **Patent No.:** **US D849,382 S**
Jenkins et al. (45) **Date of Patent:** **** May 28, 2019**

(54) **FOOTWEAR SOLE**

(71) Applicant: **TBL Licensing LLC**, Stratham, NH (US)

(72) Inventors: **Kyle M. Jenkins**, Reading, MA (US); **Pierome Sar**, Stratham, NH (US); **John Franklin**, Andover, MA (US); **Jeff Lynch**, Dover, NH (US); **Paul Grote**, Hampton, NH (US); **Suzanne Woods**, London (GB)

(73) Assignee: **TBL Licensing LLC**, Stratham, NH (US)

(**) Term: **15 Years**

(21) Appl. No.: **29/641,175**

(22) Filed: **Mar. 20, 2018**

Related U.S. Application Data

(60) Continuation-in-part of application No. 29/619,153, filed on Sep. 27, 2017, which is a division of application No. 29/572,482, filed on Jul. 28, 2016, now Pat. No. Des. 812,882.
